UNITED STATES PATENT OFFICE.

JOHN F. JENSEN, OF UNION HILL, NEW JERSEY, ASSIGNOR TO ROBERT JENSEN, OF UNION HILL, NEW JERSEY.

NON-REFILLABLE BOTTLE.

1,073,239.

Specification of Letters Patent. Patented Sept. 16, 1913.

Application filed June 11, 1912. Serial No. 702,998.

To all whom it may concern:

Be it known that I, JOHN F. JENSEN, a citizen of the United States, and resident of Union Hill, in the county of Hudson and 5 State of New Jersey, have invented a new and useful Improvement in Non-Refillable Bottles, of which the following is a specification.

This invention relates to non-refillable 10 vessels, with the object in view of providing mechanism for preventing the refilling of the vessel, which mechanism may be quickly and firmly secured to any vessel of the ordinary forms without more than a slight alteration in the said vessel.

Other objects are to provide apparatus of 15 this character which is simple, effective and clear in its operation; and which will permit the ready egress of the contents of the 20 vessel while positively preventing manual access for refilling the vessel without destroying the latter.

A further object is to provide certain improvements in the construction, form and 25 arrangement of the various parts, whereby the above-named objects may be effectively carried out.

A practical embodiment of my invention is represented in the accompanying drawings, in which—

Figure 1 represents a vertical section showing part of a conventional form of bottle with the non-refilling attachment secured therein in the position which it assumes 35 when the outlet of the bottle is above a horizontal, Fig. 2 represents a section taken in the plane of the line A—A of Fig. 1, looking in the direction of the arrows, Fig. 3 represents a section taken in the plane of 40 the line B—B of Fig. 1, looking in the direction of the arrows, Fig. 4 represents a section taken in the plane of the line C—C of Fig. 1, looking in the direction of the arrows, Fig. 5 represents a section taken in the plane of 45 the line D—D of Fig. 1, looking in the direction of the arrows, and Fig. 6 represents a section taken in the plane of the line E—E of Fig. 1, looking in the direction of the arrows.

50 The neck of the bottle is denoted by 1 and is provided near its outer end with a pair of diametrically opposed circular recesses 2 for a purpose to be hereinafter described.

55 A cylindrical cage 3, composed of porce-

lain or other suitable material, has a driving fit with the interior of the neck of the bottle, and is arranged therein with its outer edge flush with the outer end of the neck of the bottle. This cage 3 is provided with 60 a pair of diametrically opposed holes 4 arranged to register with the recesses 2 in the neck of the bottle 1. The cage 3 has, at its inner end, a valve seat 5 fitted to receive a puppet valve 6, which valve is arranged on 65 the seat so as to open outwardly. The valve 6 has a hollow stem 7 in which is secured by molten porcelain or in any other convenient manner, the end of a silk gut cord 8 which passes downwardly through the valve 6 and seat 5, and is provided at its inner end within the vessel with a marble or other weight 9, which is slightly heavier than the valve 6 and is covered by cork so as to just float.

A guide 10, flat in cross section, is secured by a driving fit at the extreme inner end of the cage 3, and has a centrally disposed vertical hole 11 through which the gut cord 8 passes for supporting the marble or other 80 weight 9 in proper position for insuring the effective operation of the apparatus.

A guide 12 is arranged by a driving fit within the cage 3 at a sufficient height above the valve seat 5 to at all times receive the 85 stem 7 of the valve, while permitting the valve to rise to the desired height from the seat for allowing the contents of the vessel to flow out. This guide 12 is cruciform in plan view, as clearly shown in Fig. 4, in 90 order that it may be readily pervious to liquid. A perforate disk 13, also having a driving fit with the interior of the cage 3, is located above the guide 12 a sufficient distance to permit an adequate opening of the 95 valve before the stem thereof engages the said disk. The perforations 14 with which this disk is provided are located at a distance from the center thereof, in order to permit the said center to be solid and act as 100 an effective means for preventing manual access to the valve from without the bottle. The apparatus further includes a cork seat which has an enlarged outer portion 15 of approximately the same diameter as the exterior to the mouth of the vessel, and a reduced portion 16 which has a tight fit with the interior of the cage 3. This reduced portion is provided with a pair of diametrically disposed recesses 17 adapted to receive 110

a pair of spring plungers 18 which are of a size fitted to pass through the holes 4 in the walls of the cage 3 and into the recesses 2 in the neck of the vessel 1 for locking the 5 cork seat 15, 16, in the cage 3 and the vessel 1, thereby also locking the cage 3 in the vessel.

A gasket or washer 19 may be located between the outer end of the vessel 1 and cage 10 3 and the inner face of the enlarged portion 15 of the cork seat. The reduced portion 16 of the said cork seat is provided with a pair of vertical holes 20 therethrough for permitting the egress of the contents of the vessel, 15 while the enlarged portion 15 has a relatively large cylindrical seat 21 for receiving a cork of the ordinary or any other desired form, which cork is indicated by 22.

In assembling the device, the vessel should 20 be provided with the recesses 2, the cage 3 with its parts in proper position forced into the neck of the vessel until its holes 4 register with the recesses 2, and then the cork seat 15, 16, forced into the cage 3 and turned 25 until the spring plungers 18 snap through the holes 4 and into the recesses 2. The vessel should, of course, be filled before the apparatus is inserted in the neck thereof. The cork 22 could then be forced into the seat 21 30 and the vessel sealed.

When it is desired to empty the vessel, it is merely necessary to remove the cork 22 and then pour out the liquid, as is done in the case of any ordinary vessel. When the 35 vessel is tilted so as to pour the contents from it, the weight 9 will fall to one side of the vessel, and slacken up on the gut cord 8 so as to permit the valve 6 to be forced from the seat 5 by the liquid, which liquid will 40 pass through the apertures in the guide 12, the disk 13 and in the cork seat 15, 16. After the vessel has been emptied, it cannot be re-filled; because as soon as its neck or outlet 45 is raised above a horizontal, the weight 9 will roll down the side of the vessel, pulling the valve 6 onto the seat 5. It will be seen that the plungers 18 prevent the removal of

any of the parts, and that the cork seat 15, 16, and the disk 13, effectually prevent manual access to the valve so as to raise it from 50 its seat.

All parts of the apparatus are composed of porcelain or other material which may be permitted to come into contact with the contents of the vessel without having any 55 deleterious effects upon the liquid; the springs for the plungers 18 being the only metallic parts.

It will be understood that various changes may be resorted to in the form, construction 60 and operation of the several parts without departing from the spirit and scope of my invention; hence I do not wish to limit myself strictly to the structure herein set forth, but

What I claim is:—

A device of the character described comprising a cage, a valve seat fitted in one end thereof, a puppet valve arranged to rest on said seat and adapted to move inwardly 70 therefrom, a perforate cork seat fitted in the other end of the cage, a perforate guard, having its perforations out of vertical alinement with the perforations in said cork seat, fitted in said cage below said cork seat, a 75 perforate guide for the stem of said puppet valve having its perforations out of vertical alinement with the perforations in said guard and said valve, mechanism consisting of a weight flexibly secured to said valve 80 and depending into the vessel, said mechanism being adapted to hold the valve on its seat when the cage is held above a horizontal with the valve seat downward, and means to secure the device in a bottle neck. 85

In testimony, that I claim the foregoing as my invention, I have signed my name in presence of two witnesses, this tenth day of June 1912.

JOHN F. JENSEN.
